UNITED STATES PATENT OFFICE

2,291,424

PUMP WITH BY-PASS VALVE

Edmund F. Wichorek, Cleveland, Ohio, assignor
to Pump Engineering Service Corporation,
Cleveland, Ohio, a corporation of Ohio

Application November 13, 1940, Serial No. 365,529

3 Claims. (Cl. 103—120)

The present invention relates to an improvement in pumps and particularly pumps of the variable displacement type wherein the displacement is adjusted in accordance with the output pressure and wherein there is provided an arrangement for bypassing fluid from the pump inlet to the pump outlet in response to an auxiliary pressure.

It is the general object of this invention to improve the arrangement and construction of the elements making up the above type of pump whereby to realize increased efficiency in operation and maintenance.

It is a more specific object to so construct a pump of the above type that important elements perform dual functions and thus eliminate the necessity of duplicating parts.

It is a still further object to provide a pump having the above advantages and in addition providing for ready reversal of operation of the pump by the simple interchange of two closure elements.

Other and more particular objects, advantages and uses of my invention will become apparent from a reading of the following specification taken in connection with the appended drawing which forms a part thereof and wherein:

Fig. 1 is a cross-section of a pump assembly incorporating a preferred embodiment of my invention; and

Fig. 2 is a cross-section taken substantially on the line 2—2 of Fig. 1.

Referring to the figures of the drawing, 10 indicates generally a pump incorporating a preferred embodiment of my invention and including essentially a variably eccentric adjustable displacement pumping assembly 11 adapted to draw fuel from inlet 12 and discharge the same from outlet 13; an arrangement of means indicated generally at 14 adapted to respond to variations in the outlet fluid pressure for adjusting the eccentricity of pumping assembly 11; and a bypass assembly indicated generally at 15 for bypassing fluid from the inlet 12 to the outlet 13 around pumping assembly 11.

Certain important elements forming part of the displacement adjustment control means 14 and the bypass assembly 15 perform dual functions in the respective assemblies and it is to this novel arrangement among others that my invention is particularly directed.

Pumping assembly 11 may take any one of several well known forms. However, I prefer the general arrangement shown which is described

in detail and claimed in Johnson Patent No. 2,192,660.

The bypass assembly 15 is defined in part by a first upstanding wall 21 forming a nipple-like protuberance, a second generally concentric upwardly extending wall 22 spaced radially outwardly from wall 21 and defining an annular bypass chamber therebetween. For the purpose of closing the upper extremities of walls 21 and 22 to thus define a by-pass chamber 23 as well as to in part define a lower diaphragm chamber 24, I have provided a novel partition closure and bearing member indicated generally at 25. This member 25 comprises a downwardly depending tubular nipple portion 26 externally threaded for reception in engagement with the internal threads of vertical wall 21 and formed internally with a cylindrical bore 27 for substantially sealed cooperation with piston-like connecting link 28 between pumping assembly 11, and diaphragm assembly 29 of displacement control means 14. Member 25 is further provided with a radially outwardly extending flange or cover portion 30 functioning to cover the upper extremities of walls 21 and 22 to thus complete the formation of bypass chamber 23 and lower diaphragm chamber 24.

Upwardly extending wall 22 is formed with a first port 31 adapted to be placed in communication with outlet 13 and a second generally opposed port 32 in communication with the pump inlet. As will be seen, the inlet and outlet may be reversed.

Arranged for interchangeable cooperation with the ports 31 and 32 depending upon the desired direction of operation of the pump, I have provided a novel valve assembly indicated generally at 34 and including a disc-like valve 35 shown in engagement with port 31. Extending from the rear face of valve 35 is a hollow tubular piston-like protuberance 36 arranged to be supported in the cylindrical bore of a removable threaded plug 37. Interposed between the plug and valve within tubular protuberance 36 is a compression spring 38 functioning to urge valve 35 into engagement with seat 31 with a pressure in accordance with the adjustment of threaded plug 37 with respect to the supporting housing. The pump housing is formed in opposed relation to each of the ports 31 and 32 with identical threaded openings 41 and 42 for the selective reception of threaded plug 37. The flange 43 extends radially from one end of plug 37 and is arranged to engage the usual sealing gasket between it and the adjacent housing. Interme-

diate this flange 43, and the inner end of plug 37, there is formed a circular channel 44 extending about the periphery of the plug. Communicating between the forward end of plug 37 and channel 44 is an additional passage 45. While I prefer to form passage 45 within the body of the plug as shown, it will be understood that the same may take the form of an axially-extending channel bisecting the peripheral thread on the plug.

A pair of substantially identical housing passages 47 and 48 have their inner ends communicating with the lower diaphragm chamber 24 and their opposite terminals communicating with the housing plug receiving openings 41 and 42 intermediate the ends thereof. These terminal portions of passages 47 and 48 are so disposed that with plug 37 in position with either opening 41 or 42, circular groove or channel 44 will be in communication with the respective terminal end of either passage 47 or 48 thus serving to place the respective port 12 or 13 as the case may be in communication with the underside of the diaphragm for the purpose of controlling the displacement of the pump assembly 11 in accordance with the discharge pressure. With plug 37 located in opening 41 and the pump arranged to operate in a counterclockwise direction, the opposite opening 42 in the housing adjacent the port 32 is closed by a blind plug 51, the peripheral surface portion of which closes the outer terminal of passage 48 leading from the lower diaphragm chamber.

It will be readily apparent that the direction of operation of pump 10 may be quickly changed merely by interchanging valve assembly 34 including plugs 37 with blind plug 51.

In addition to the above there will of course be provided the usual conventional pump elements forming no particular part of the present invention other than in combination, such for example as the elements described in greater detail in the above referred to Johnson patent.

While I have described my invention in connection with a specific embodiment thereof, it will be understood that this is by way of example only and not by way of limitation, it being intended that my invention be defined solely by the appended claims which should be given a scope as broad as commensurate with the prior art.

I claim:

1. In a variable displacement pump assembly including means defining a housing formed with a pumping chamber having an inlet port and an outlet port and adapted to receive a rotary adjustable displacement pumping assembly, means responsive to outlet pressure for adjusting the displacement of said pumping assembly including a flexible diaphragm and connecting piston-like link means extending between the central portion of said diaphragm and said pumping assembly, means defining a bypass assembly for bypassing fluid around said pumping assembly from said inlet to said outlet in response to auxiliary fluid pressure, said last named means including a tubular protuberance extending outwardly from said housing and surrounding said piston-like link, a surrounding wall portion spaced radially from the outer periphery of said tubular protuberance, said wall being formed with a first port in communication with said inlet port and a second port opposite said first port in communication with said outlet port, a combination closure for the upper extremities of said tubular protuberance and said surrounding wall

and cylinder for the reception of said connecting link comprising a member having a centrally depending exteriorly threaded nipple portion threadably received in engagement with complementary threads formed on the inner periphery of said tubular protuberance, said member being formed with a cylindrical interior for the reception of said piston-like link in sealable reciprocal cooperation therewith and further formed with a radially outwardly extending flange portion functioning as a cover for said upper extremities and defining with portions of said housing which are arranged adjacent to said flange portion and with said diaphragm a lower diaphragm chamber, a valve assembly including a valve for cooperation with said second port in said wall, said assembly being characterized by the inclusion of a first exteriorly threaded plug threadably mounted in a complementarily formed opening in said housing and provided with a passage therein communicating at one end with said pump outlet and having a second terminal portion adjacent the periphery of said plug intermediate the ends thereof normally disposed within the confines of said complementarily formed opening in said housing, said housing being formed with a passage communicating at one end with said lower diaphragm chamber and at the other end with said terminal portion of said passage in said plug, said plug being formed with a cylindrical recess for receiving a piston-like extension protruding from the rear of said valve and a coil compression spring positioned between said plug and said valve for normally urging the latter into engagement with said port with a predetermined force depending upon the adjustment of said plug effected by turning the same on said thread and a second threaded opening formed in said housing in opposed relation to said first named port, a second passage formed in said housing communicating at one end with said lower diaphragm chamber and at the other end with said last named threaded opening intermediate the ends thereof and a second threaded plug adapted to be received in said last named threaded opening and effective to close said second housing passage, said arrangement being such that said threaded plugs may be interchanged for the purpose of maintaining the means responsive to outlet pressure and said bypass assembly operative upon reversal of the direction of operation of said pump.

2. The combination defined in claim 1 wherein said first named threaded plug is formed at the outer terminal portion thereof with a radially extending flange functioning to limit the movement of said plug inwardly, an annular groove formed about the periphery of said first plug between said flange portion and the inner terminal portion thereof, said passage formed in said first plug leading from the inner terminal portion thereof to a point in communication with said annular groove, said first housing passage arranged to communicate with said annular groove when said plug is in position within said threaded opening.

3. In a variable displacement pump assembly including means defining a housing formed with a pumping chamber having an inlet port and an outlet port and adapted to receive a rotary adjustable displacement pumping assembly, means responsive to outlet pressure for adjusting the displacement of said pumping assembly including a flexible diaphragm and connecting piston-like link means extending between the central portion of said diaphragm and said pumping assembly, means defining a bypass assembly for bypassing fluid around said pumping assembly from said inlet to said outlet in response to auxiliary fluid pressure, said last named means

including a tubular protuberance and said surrounding wall

central portion of said diaphragm and said pumping assembly, means defining a bypass assembly for bypassing fluid around said pumping assembly from said inlet to said outlet in response to auxiliary fluid pressure, said last named means including a tubular protuberance extending outwardly from said housing and surrounding said piston-like link, a surrounding wall portion spaced radially from the outer periphery of said tubular protuberance, said wall being formed with a first port in communication with said inlet port and a second port opposite said first port in communication with said outlet port, a combination closure for the upper extremities of said tubular protuberance and said surrounding wall and cylinder for the reception of said connecting link comprising a member having a centrally depending exteriorly threaded nipple portion

5 threadably received in engagement with complementary threads formed on the inner periphery of said tubular protuberance, said member being formed with a cylindrical interior for the reception of said piston-like link in sealable reciprocable cooperation therewith and further formed with a radially outwardly extending flange portion functioning as a cover for said upper extremities and defining with portions of said housing which are arranged adjacent to said flange portion and with said diaphragm a lower diaphragm chamber, a pressure responsive bypass valve assembly cooperating with said second port in said wall, and means placing said lower diaphragm chamber in communication with said outlet port.

EDMUND F. WICHOREK.
